UNITED STATES PATENT OFFICE.

FRANK A. RICHARDS, OF VALLEY FALLS, RHODE ISLAND.

DESIGN FOR A FOOT-STOOL.

SPECIFICATION forming part of Design No. 22,549, dated June 20, 1893.

Application filed April 21, 1893. Serial No. 471,346. Term of patent 7 years.

To all whom it may concern:

Be it known that I, FRANK A. RICHARDS, of Valley Falls, in the county of Providence and State of Rhode Island, have invented and 5 produced a new and original Design for Foot-Stools and Similar Articles, of which the following is a specification, reference being had to the accompanying drawings, forming part thereof.

10 Figure 1 of the drawings is a view of a foot-stool representing my new design. Fig. 2 is a vertical sectional view of the same to more clearly indicate the features of the design.

The leading features of my new design for 15 foot-stools and similar articles consist of the circular outline, broken by an inwardly-extending opening between two arms, curving depressions in the surface, small square projections symmetrically arranged in the de- 20 pressions, raised ornaments on the ends of the arms, and a similar but somewhat lengthened ornament intersecting the curved outline together with the central cushioned effect.

Number 3 in the drawings represents the top 25 of a foot-stool, and 4 is one of the standards on which the top is supported. Beginning at the base portions 5—5 of the top the outline of the same extends in slightly elliptical curves to the upper portion 6, from 5—5 the outline

slants inwardly in straight lines to 7—7, thence 30 curves outward to 8—8, and finally curves abruptly inward to the nearly straight line 9.

Near the upper portion 6 is located the straight beveled ornament 10, and from 5 to 7 extend the beveled ornaments 11—11, while 35 located between the points 5—5 and the upper portion 6, in the surface of the top 3, are the curving depressions 12—12 in each of which are located the square ornaments 13—13 graduated in size. 40

The central portion of the top 3 is ornamented by a cushion 14 having a broad base, the line of which curves slightly inward; from the ends of the base line the outline of the cushion curves upward following the general outline of the top 3, and around the cushion is a border 15, the whole presenting the effect of a cushion surrounded by a frame. 45

What I claim is—

The design for a foot-stool or similar article as herein shown and described. 50

In witness whereof I have hereunto set my hand.

FRANK A. RICHARDS.
